Des. 230,572

Patented Mar. 5, 1974

230,572

PACKAGING CONTAINER FOR LIGHT BULBS OR THE LIKE

Joseph R. D'Alessio, Lunenburg, Mass., assignor to Rand-
Whitney Packing Corporation, Leominster, Mass.

Filed May 12, 1972, Ser. No. 252,952

Term of patent 14 years

Int. Cl. D9—03

U.S. Cl. D9—224

E-I-23.

FIG. 1 is a top, front perspective view of a packaging container for light bulbs or the like showing my new design;

FIG. 2 is a bottom left side perspective view thereof;

FIG. 3 is a bottom view thereof;

FIG. 4 is a top rear perspective view thereof;

FIG. 5 is a front elevation view thereof; and

FIG. 6 is a top view thereof.

I claim:

The ornamental design for a packaging container for light bulbs or the like, as shown.
